HEATER DUCT

Joseph Ledwinka, Philadelphia, and George Trautvetter, Jenkintown, Pa., assignors to Edward G. Budd Manufacturing Company, Philadelphia, Pa., a corporation of Pennsylvania

Application September 4, 1943, Serial No. 501,340

2 Claims. (Cl. 257—136)

1

The invention relates to a heater duct especially for vehicles and more particularly for passenger rail cars.

More specifically, the invention relates to improvements in the type of heater duct comprising a housing arranged along the corner of the floor and a vertical wall of the room to be heated, which housing contains the heater elements such as a steam or hot water radiator, though other types of heater, for instance electric heaters, may be used in connection with the invention.

Among the objects of the invention are simplicity of construction, easy accessibility, efficient heating and, above all, comfort for the occupants by eliminating overheated zones with which the occupants have to or may come in contact.

The above and other objects are achieved by a heater duct of the indicated type having along the vertical wall a shallow upward extension provided near its upper margin with openings communicating with the interior of the room, the extension acting like a chimney which promotes the circulation of air across the radiator and counteracts the accumulation of hot air under the top of the main body of the duct. This last-named feature considerably improves the comfort of rail car passengers whose feet or lower leg portions were often overheated by the overheated top portion of the hitherto customary heater duct.

The features of the invention, its objects and advantages will be more fully understood from the embodiment illustrated in the attached drawing and described in the following:

The drawing is a fragmentary perspective view of the lower longitudinal margin of the interior of a passenger rail car body and of a heater with heater duct or housing.

1 designates the side sill of the car body. The upper arm 2 of sill 1 carries the floor 3 and, partly by means of a Z-section rail 4, the horizontal arm 5 of an angle section panel strip. The second arm 6 of said last-named strip extends upwardly and is continued by a corrugated panel 6'. The arm 6 and panel 6' are attached to vertical posts 7 (one only is shown) which have their lower ends anchored to the sill 1. At certain intervals along the edge of the floor, frames 8 are arranged which support a heating pipe 9 with its heat exchange fins 10 by means of an insulating layer and a clip 11 for each frame. 12 is the return pipe for the heating medium. An angle section strip 13 has one arm secured to the panel arm 6; the other arm of this strip is provided with holes 13' near the apex of the angle and serves for the attachment of the upper part of the

2

frames 8 at any desired locations along its longitudinal extent. The cold and hot water pipes 14, 15 are attached to the panel arm 6.

A panel strip 16 and the flange along the margin 5 of the horizontal arm 17 of another generally angle-section panel strip are secured by screws 18 to said frames 8. The other arm 19 of the last-mentioned panel strip extends upwardly and has its upper margin secured by screws 20 to the panel 6' so that its main body is held at a short distance from the panel 6'.

Panel 16 is provided with a row of vertical slots 21 and has its lower margin spaced from the floor so that cool air may enter at the bottom and leave, 15 after having passed the radiator 9, 10, through the slots 21.

The arm 19 is provided near its upper margin with another set of slots or louvres 22 which serve together with the space 23 between arm 19 and 20 panels 6, 6' for the discharge of hot air which would otherwise accumulate beneath the arm 17. The space 23 acts like a chimney.

The provision of the space 23 and the louvres 22 prevents uncomfortable overheating of the top 25 17 and it insures also a more uniform distribution of the heated air which is no more, as in the customary constructions, exclusively discharged at one level, namely, the openings 21, but part of which is now discharged at a higher level and 30 closer to the wall through the louvres 22.

The upper margin of arm 19 serves as a kick-board and for holding the lower margin of a trim panel 24.

The illustrated embodiment is, of course, liable 35 to many modifications without departing from the invention as defined by the annexed claims.

What is claimed is:

1. A heating installation for a compartment having a floor and a vertical side wall meeting in 40 a corner, comprising in combination, a housing in the compartment corner, the housing having an imperforate horizontal wall spaced above the floor, a vertical wall at a relatively great distance from the compartment side wall joining and extending 45 down from the outer edge of the horizontal wall to a point near but spaced from the floor, said housing side wall having heat outlet openings near the top only, a second vertical wall at a relatively small distance from said compartment side 50 wall joining and extending up from the inner edge of the horizontal wall to a height along the compartment side wall well above the horizontal wall and there being closed against the compartment side wall, said second vertical housing wall 55 having heat outlet openings near the top only,

and a heating element beneath said horizontal wall, the arrangement being such that cool air from the compartment enters beneath the first vertical housing wall, is heated by said heating element and the heated air is restricted against upward movement by said horizontal wall, some escaping through the top openings of the first vertical housing wall and some being drawn in stack fashion up the narrow space between the second vertical housing wall and the compartment wall and escaping through the top openings in the second vertical housing wall.

2. A heating installation for a compartment having a floor and a vertical side wall meeting in a corner, comprising in combination, a housing in the compartment corner, the housing having an imperforate horizontal wall spaced above the floor, a vertical wall at a relatively great distance from the compartment side wall joining and extending down from the outer edge of the horizontal wall to a point near but spaced from the floor, said housing side wall having heat outlet openings near the top only, a second vertical wall at a relatively small distance from said compartment side wall joining and extending up from the inner

10

25

edge of the horizontal wall to a height along the compartment side wall well above the horizontal wall and there being closed against the compartment side wall, said second vertical housing wall having heat outlet openings near the top only, and a heating element beneath said horizontal wall, the arrangement being such that cool air from the compartment enters beneath the first vertical housing wall, is heated by said heating element, and the heated air is restricted against upward movement by said horizontal wall, some escaping through the top openings of the first vertical housing wall and some being drawn in stack fashion up the narrow space between the second vertical housing wall and the compartment wall and escaping through the top openings in the second vertical housing wall, said housing also including a horizontal plate with flow restricting openings at the level of said first horizontal plate disposed at the bottom of the second vertical housing wall and across the space between the first horizontal wall and the side wall of the compartment.
